UNITED STATES PATENT OFFICE

CHARLES H. KESTENMAN, OF PROVIDENCE, RHODE ISLAND, ASSIGNOR TO KESTENMAN BROS. MFG. CO., OF PROVIDENCE, RHODE ISLAND, A CORPORATION OF RHODE ISLAND

EXTENDIBLE CLASP OR CONNECTING DEVICE FOR STRAPS, BANDS, AND BRACELETS

Application filed August 12, 1931. Serial No. 556,516.

This invention relates to improvements in buckles, clasps and like devices for securing the ends of wrist-watch straps, bands, bracelets and similar articles.

One object of the invention is to provide an extendible fastening-device on the strap, band or bracelet which, after the latter has been adjusted to the proper length to fit the wrist, may be released and opened out to allow the strap, band or bracelet to be slipped over the hand without unfastening its ends.

Another object of the invention is to provide a fastening-device of the type specified composed of a plurality of foldable members one of which constitutes a means for slidably holding one end of the strap, band or bracelet whereby it may be slid therealong to further expand the length of the bracelet to provide greater convenience in placing it on and removing it from the wrist.

Another object of the invention is to provide a fastening-device of the type specified having improved means at its ends for securing the ends of the strap, band or bracelet to the device.

Another object of the invention is to provide a fastening-device of the type specified having detent-means incorporated therein for holding the parts of the clasp in closed relationship to effect a secure joinder between the ends of the strap or bracelet without chance of their becoming accidentally unclasped or detached.

Another object of the invention is to provide a device of the type specified which is comprised of a minimum number of parts adapted for economical manufacture from sheet-metal, and which may be easily and inexpensively assembled without the use of solder screws, rivets or other extraneous parts.

Another object of the invention is to provide a device of the type specified having a neat and ornamental appearance with its mechanical elements entirely hidden from view, and which is free from unsightly projections or sharp edges on its surfaces liable to scratch or irritate the skin of the wearer.

Further objects of the invention are set forth in the following specification which de-

scribes a preferred embodiment of the invention, by way of example, as illustrated by the accompanying drawing. In the drawing:

Fig. 1 is a perspective view of a conventional form of wrist-watch having a two-part strap attached thereto with its ends secured together by the present improved extendible clasping-device; 55

Fig. 2 is an enlarged longitudinal sectional view of the fastening-device showing the parts in clasped relationship; 60

Fig. 3 is a similar view illustrating the manner in which the parts are unclasped and three of its members unfolded to extend the length of the bracelet; 65

Fig. 4 is a side view illustrating the manner in which an additional member is opened out to further extend the length of the bracelet; 70

Fig. 5 is a similar side view showing the device fully extended or opened out to permit removal of the band or bracelet from the wrist; 75

Fig. 6 is a plan view of the same; and

Fig. 7 is a composite perspective view of the several members employed for securing one end of the bracelet to the device. 80

The present improved device comprises, in general, a series of cooperating members which are hingedly connected at their ends to adapt them to be folded into closed relationship, one over the other; or to be opened out into extended position to lengthen the strap, band or bracelet which has its ends connected thereto. The opposite sections of the strap, band or bracelet are pivotally attached to the free ends of the device so that when the parts thereof are folded into overlying relationship the strap, band or bracelet will be drawn tight around the wrist; and when the folding elements are opened out the bracelet will be lengthened to a considerable extent to adapt it to slip over the hand of the wearer. The present improvement relates particularly to an additional folding and sliding means which may be operated at will to further extend the fastening-device whereby to provide for greater extension in the length of the bracelet. 85 90 95

Referring to the drawing, 2 designates a conventional type of wrist-watch having bails 100

3 on its sides to which the ends of the opposite strap-sections 4 and 5 are attached by means of connectors 6. The present improved extendible fastening-device is herein shown as applied to use with a strap or bracelet composed of articulated links, but in other cases it may be employed with a reticulated fabric or leather strap having an end cross-piece or bar. The term strap is therefore herein employed in a generic sense to designate any such form of band or bracelet.

The main portion of the clasp comprises three cooperating extension-members, namely, a base-element 7, a connecting-element 8 and a top-element or cover 9. These members may be constructed of thin sheet-metal plates and curved to conform to the contour of the wearer's wrist. The base-member 7 is constituted by a relatively flat plate 10 with side-flanges 11 folded upwardly therefrom. The plate 10 is provided at its ends with pairs of spaced ears or tabs which are bent around to form loops 12 and 13 for receiving hinge-pins 14 and 15, respectively, which are used for a purpose as later explained. The side-flanges 11 are cut away at 16 and 17 to provide clearance for other parts later described. Elongated detent-openings 18 punched through the side-flanges 11 cooperate with detent-protuberances on the member 9, to be later described, to secure the parts of the clasp in closed or clasped relationship.

The connecting-plate 8, previously mentioned, comprises a strip of sheet-metal having at one end a loop or bearing 20 by means of which this member is pivoted on the hinge-pin 15 between the loops 13 on the base-member 7. The member 8 is narrowed in width to permit it to be folded over the base-member 7 between the upstanding side-flanges 11 thereof. The opposite end of the connecting-member 8 is provided with a slightly wider loop or bearing 21 adapted to pivot on a pin 25 extending between the sides of the top-member or cover 9.

The top-member or cover 9 is of inverted U-shape in cross-section, having a top-wall 22 with side-flanges 23 folded downwardly therefrom. The top-wall 22 is extended at one end to provide a curved lip 19 adapted to serve as a finger grip in opening the clasp. Its flanges 23 are indented on the outside to form inwardly projecting protuberances or projections 24 of substantially rectangular outline, see Figs. 5 and 6, which are adapted to snap into the detent-openings 18 in the base-member 7 when the parts are folded into closed or clasped relationship. The hinge-pin 25 for the connecting-member 8 is held in apertures in the side-flanges 23 with its ends riveted over to retain it in place. At the opposite end of the top-member 9 is a second hinge-pin 26 which extends through circular holes punched in the side-flanges 23 with its ends riveted over thereagainst.

Adapted to pivot on the hinge-pin 26 is a link-connector for securing the bracelet section 5 to the clasping-device. The connector-link is constructed of two parts designated 29 and 30 and shown in detail in Fig. 7. The upper-element 29 comprises a strip of sheet-metal bifurcated at one end to provide a pair of spaced ears which are curled around to form loops or bearings 31. The opposite end is narrowed in width to form an extension which is bent around in a hook 32. The co-operating member 30 comprises a relatively narrow strip of sheet-metal having one end curled over to form a loop 34 and bent into a hook 35 at its opposite end.

To assemble the connector-link on the clasp-member 9, the members 29 and 30 are placed between its side-flanges 23 and the pin 26 inserted through their loops 31 and 34 and riveted over against the side-flanges in the manner as illustrated in Fig. 6. To secure the section 5 of the bracelet strap to the clasp-element 9 its end cross-bar is placed within the hook 35 of the lower connector-member 30, and the upper connector-member 29 is engaged thereover with its hook 32 snapped over the hook 35 to lock the parts together.

In most clasping-devices of the present type the opposite strap sections are connected directly to the ends of the folding-members without provision for extension in the length of the bracelet beyond that allowed by the unfolding of the several members. With such a form of construction it is often found that the expansion in the length of the bracelet is insufficient to allow it to be slipped over the hand, especially in the case of bracelets intended for use by men.

To avoid this deficiency the present invention contemplates the use of an additional folding member 40 which is pivoted to the end of the base-member 7 and provided with means slidable therealong for attaching the end of the opposite strap section 4 to the clasp. This improved construction increases the expansion range of the device practically two-fold. The member 40 is constructed of relatively narrow sheet-metal with one end bent around to form a loop 41 for pivotally connecting it with the hinge-pin 14, previously referred to as extending through the loops 12 on the base-member 7. The opposite end of the member 40 is provided at its sides with laterally extending projections or lugs 42, see Fig. 7, which serve as abutments or stops for limiting the sliding movement of a member 45 therealong.

The member 45 consists in an inverted U-shaped slide having a top-portion 46 and depending legs 47. Circular holes are punched through the legs 47 to receive a pivot-pin 48 and pivoted on the pin 48 are two connector-members 29 and 30 of the same construction as those used for attaching the strap section 5 and previously described. The

members 29 and 30 are assembled on the slide-member 45 between its legs 47 in the manner as clearly illustrated in Figs. 6 and 7, and are employed for securing the end of the strap section 4 to the clasp.

Having now described the construction and arrangement of the several parts of the improved clasping-device, its method of operation will next be explained. In applying the bracelet to the wrist the clasp is opened out or extended as shown in Figs. 5 and 6 to provide expansion in the length of the bracelet whereby it may be slipped over the hand. To clasp the bracelet around the wrist the member 45 is first slid along the member 40 to a point adjacent the pivot-pin 14. The extension-member 40 is then folded over the base-member 7 in the manner as illustrated in Figs. 2 and 3. The two members 8 and 9 are next folded over the extension-member 45 as shown in Figs. 2 and 3 and the top-member or cover 9 is finally pressed downwardly until its detent-protuberances 24 snap into the detent-openings 18 in the sides of the base-member 7.

The sections 4 and 5 of the bracelet will thus be drawn tightly around the wrist and the parts of the device securely clasped together in folded relationship to prevent unwarranted or accidental unfastening thereof. It will be noted by reference to Figs. 1 and 2 that the side-flanges 23 of the top-member 9 overlie the side-flanges 11 of the base-member 7 so that the mechanical parts of the device are entirely concealed from view.

When it is desired to remove the bracelet from the wrist, the device is unclasped by inserting the finger-nail under the lip or extension 19 on the cover 9 and lifting the latter upwardly to free its protuberances 24 from the openings 18 in the base-member 7. The cover 9, together with the connecting-member 8, are swung outwardly on their pivots 15 and 25 in the manner as illustrated in Fig. 3. When the parts are opened in end-to-end relationship as illustrated in Figs. 4, 5 and 6 the bracelet is expanded in length to a considerable extent and to provide additional expansion the member 40 is swung back on its pivot 14 as shown in Fig. 4. This latter expansion is accomplished by raising the member 40 to cause the member 45 to slide outwardly therealong until it brings up against the abutments 42, see Figs. 5 and 6. This latter extension of the clasp expands the bracelet to the maximum extent so that it may be conveniently slipped over the hand in placing it on or removing it from the wrist.

It will be observed from the foregoing that the present invention provides an improved clasping-device having a maximum capacity of extension for the purposes specified. The various parts of the clasp may be stamped from sheet-metal to render them light in weight and economical to manufacture, yet

in their assembled relationship they provide a strong durable construction. When in closed or clasped relationship the mechanical elements of the device are concealed by the cover 9 which may be suitably embossed, engraved or otherwise embellished on its outer face to enhance the artistic appearance of the whole article.

A particular feature of improvement in the present invention consists in the additional expansion means which enables the wearer to extend the bracelet to a very considerably length to provide greater convenience in applying it to the wrist or removing it therefrom.

The elongated detent-means for clasping the members in closed relationship provide adequate engaging surfaces to effect a positive and secure clasping of the parts.

While I have herein shewn and described a preferred form of construction of the improved clasp, it is to be understood that various modifications may be made in the structure and arrangement of its parts without departing from the spirit or scope of the invention. Therefore, without limiting myself in this respect, I claim:

1. In a device of the type specified, the combination of a base-member, an extension-member hinged to one end of the base-member to adapt it to fold against the latter, a slide on said extension-member slidable between its hinge and free end, means for connecting the slide to the end of a bracelet, a second extension-member hinged to the opposite end of the base-member, a top-member hinged to the outer end of the second extension-member, and means for connecting the top-member to the opposite end of the bracelet.

2. In a device of the type specified, the combination of a base-member, extension-members hinged to the opposite ends of said base-member to adapt them to fold into overlying relationship therewith, a cover-member hinged to the free end of one of said extension-members, a slide slidably longitudinally of the other extension-member and constructed to adapt it to move toward the hinge of said extension-member when the latter is folded into overlying relationship with the base-member, means for connecting the slide to one end of a bracelet, and means for connecting the cover-member to the opposite end of the bracelet.

3. In a device of the type specified, the combination of a base-member, an extension-member hinged to one end of the base-member, a top-member hinged to said extension-member and provided with means for connecting it to the end of a bracelet, a second extension-member hinged to the opposite end of the base-member and provided with a stop at its free end, and a slide slidable on the second extension-member between its hinge

and stop and having means for connecting it to the opposite end of the bracelet.

4. In a device of the type specified, the combination of a base-member, extension-members hinged to the opposite ends of said base-member to adapt them to be folded into overlying relation therewith, a slide slidable longitudinally of one of said extension-members, means for connecting the slide to the end of a strap or bracelet, a cover-member hinged to the end of the opposite extension-member to adapt it to fold over the top of the base-member when the extension-members are folded into overlying relation therewith, means for clasping the cover-member in folded position on the base-member, and means for connecting the opposite end of the strap or bracelet to the free end of the cover-member.
5. In a device of the type specified, the combination of a base-member having a bottom and side walls, extension-members hinged to the opposite ends of said base-member to adapt them to be folded into nested relationship within its side walls, a slide slidable longitudinally on one of said extension-members, means to limit the sliding movement of said slide, means for attaching the end of a strap or bracelet to the slide, a cover-member hinged to the opposite extension-member and formed with a top and side walls adapted to overlap the side walls of the base-member when the parts are folded into overlying relationship, and means for attaching the opposite end of the strap or bracelet to the cover-member.
6. In a device of the type specified, the combination of a base-member, an extension-member hinged to each end of the base-member, a cover-member hinged to the outer end of one of said extension-members to adapt it to fold into overlying relationship with the base-member, one of said extension-members being foldable against the base-member beneath the opposite extension-member, a slide slidable longitudinally of said extension-member to adapt it to slide outwardly thereon when said extension-member is opened into extended position and to slide inwardly toward the hinge of said member when the latter is closed against the base-member, means for connecting the slide to the end of a strap or bracelet, and means for connecting the opposite end of the strap or bracelet to the free end of the cover-member.

In testimony whereof I hereunto affix my signature.

CHARLES H. KESTENMAN.
